UNITED STATES PATENT OFFICE.

WILLIAM H. KOONS, OF BATH, PENNSYLVANIA, ASSIGNOR OF TWO-THIRDS
TO PALMER M. KERN AND HARRISON A. GERNERD, OF SAME PLACE.

WINDOW-SASH HOLDER.

SPECIFICATION forming part of Letters Patent No. 584,310, dated June 8, 1897.

Application filed August 17, 1896. Serial No. 602,955. (No model.)

To all whom it may concern:

Be it known that I, WILLIAM H. KOONS, a citizen of the United States, residing at Bath, in the county of Northampton and State of Pennsylvania, have invented certain new and useful Improvements in Window-Sash Holders; and I do hereby declare the following to be a full, clear, and exact description of the invention, such as will enable others skilled in the art to which it appertains to make and use the same.

My invention relates to certain new and useful improvements in sash-holders, the object of the same being to provide a simple and cheaply-constructed device of this character whereby window-sashes may be readily raised or lowered and locked at any point within their range of movement.

The invention consists of a window-sash having a recess or socket in its outer edge, a dog having a cam-face pivoted in said socket and projecting outwardly from the edge of said sash, a pin pivoted to the end of said dog and projecting through a slot in the inner edge of said window-sash, and a spring surrounding said pin for normally urging said dog to its outer position.

The invention is clearly illustrated in the accompanying drawings, in which—

Figure 1 represents a front elevation, partly in section, of a window frame and sash with my improved fastening device secured in the latter. Fig. 2 is a view of the outer edge of the sash.

Like reference-numerals indicate like parts in both views.

The window-frame 1 has the sash 2 slidably mounted therein, both being of the usual form of construction except as hereinafter set forth. The sash 2 has formed in its outer edge a recess or socket 3, in which is pivotally mounted a dog 4, having a cam-face which projects slightly beyond the outer edge of said sash. Pivoted to the free end of said dog is a rod or bar 5, which extends inwardly through

a slot or opening 6 in said sash and has formed upon its inner end a knob or handle 7. Surrounding the rod or pin 5 and engaging the shoulder on the inside of the socket 3 is a coil-spring 8, which tends to normally urge the dog 4 outwardly.

My improved sash-holder has been shown in the drawings in connection with the lower sash of a window. It will thus be seen that the sash 2 is free to be moved upwardly, but that its downward movement is prevented by reason of the engagement of the dog 4, projecting outwardly from the edge of said sash, with the inner surface of the window-frame 1. The greater the pressure that is applied to force the sash 2 downwardly the stronger the same will be resisted by the dog 4 by reason of the cam-shaped face thereon. If it be desired to lower said sash, it may be readily done by drawing inwardly the rod or bar 5, which will release the dog 4 from engagement with the inner surface of the window-frame 1.

Having now described my invention, what I claim as new, and desire to secure by Letters Patent, is—

The combination with a window-frame having smooth inner edges, of a sash slidably mounted therein having a recess or socket in its outer edge, a cam-faced dog pivoted in said socket, a rod or pin pivoted to the end of said dog and projecting inwardly through a slot or opening in said sash, and a coil-spring surrounding said rod, whereby said dog is normally urged outwardly into engagement with the inner surface of said window-frame, and whereby the same may be released therefrom, substantially as described.

In testimony whereof I have signed this specification in the presence of two subscribing witnesses.

WILLIAM H. KOONS.
